APPARATUS FOR POLISHING FINGER NAILS

Alfredo Waldemar Doux, Vienna, Austria, assignor of one-third to Theodor von Hoffmann-Ostenhof and one-third to Franz Hochmayer, both of Vienna, Austria

Application January 22, 1934, Serial No. 707,807
In Austria July 13, 1933

8 Claims. (Cl. 132—74)

This invention relates to an apparatus for polishing finger-nails comprising a grip, provided with depressions, excavations or recesses into which are placed the finger-tips, and a 5 polishing ring mounted rotatable on said grip for simultaneously polishing the nails of the five fingers.

The essential feature of the present invention consists in that the polishing ring which is in 10 the form of an elastic cushion is arranged preferably removable in a box-shaped casing which is open at one side and is mounted rotatable with respect to the grip. If desired a handle is secured to the casing for rotating the casing with 15 respect to the grip held fast by the fingers to be polished. In view of this arrangement it is possible to subject the finger-nails to a feeling treatment.

The handle can be dispensed with and the 20 polishing apparatus may consist of two polishing rings which are rotatably connected with their respective grip and are arranged behind each other in a plane and in this position are connected to form a unit, which by means of 25 the fingers holding the grips are moved in the path of a circle for polishing the nails of both hands.

Two modes of carrying out the present invention are illustrated by way of example on 30 the accompanying sheet of drawing in which Figs. 1 and 2 show a polishing apparatus with a single casing in front view and in cross section respectively. Figs. 3 and 4 illustrate in cross section a double-casing apparatus in the 35 operative position and in the inoperative position respectively.

The polishing apparatus consists of a disc-grip 1 provided at its periphery with a number of grooves 2, adapted to the fingers of a hand. The grip 1 is mounted on and rotatably connected 40 with the shaft 3 of a box-shaped casing 4, which is open at one side and in which is fitted a removable annular polishing cushion 5, the yielding polishing face 11 of the latter being disposed 45 opposite the grooves or notches of the grip at a distance corresponding to the average breadth of a finger. The annular polishing cushion 5 is secured removably in the casing by a tensioning spring 12 and its polishing face is wavy or formed uneven in suitable manner, in order to promote 50 or facilitate that the polishing face is closely applied to the finger-nails. The shaft 3 is fixed for instance to the bottom wall of the casing and is rotatably mounted in the grip. The latter and the shaft are disengageably connected with each 55 other by a screw 6 which is screwed into the grip

and engages an annular groove of the shaft. A handle 7 is hinged to the outside of the casing 4 and in its inoperative position is folded back onto the bottom side of the casing 4 in such a manner, that it does not project in front of the casing and the knob 8 of the handle 7 passes through a hole in the bottom side of the casing.

When the polishing apparatus is used, the five fingers of a hand hold the grip in such a manner, that each finger rests in the groove corresponding to its breadth, and now the polishing ring 5 is rotated by the free hand turning the handle 7, whereby all five finger-nails are polished simultaneously.

Figs. 3 and 4 show an apparatus for polishing 15 the nails of both hands at the same time. In this case two polishing rings are connected with one another in such a manner, that their grips are freely accessible from opposite sides. Both polishing devices are of like construction and 20 they are joined inseparably or in the manner shown in Fig. 3. In this construction, the grips 1 are arranged slidably on the shafts and are elastically supported by springs.

One of the casings 4 is provided with a hook 9, 25 while the other casing is furnished with a pocket 10 which is engaged by the hook 9 if, in use, the grips of both polishing devices are pressed into their casings by the fingers of the two oppositely 30 acting hands. The grips are pressed by the finger-tips and against the action of the springs into the casings to such an extent, that finger-nails rest well on the polishing faces. In order 35 to polish the nails of both hands at the same time, the polishing apparatus is rotated by the fingers holding the grips in a circular path, described jointly by both hands and the centre of which lies in a point of the connecting place of both casings.

After their separation, the casings of both 40 polishing devices can be fitted together so as to prevent a dust-tightly closed box.

What I claim is:—

1. Apparatus for polishing finger-nails comprising in combination a casing with an opening 45 at one side, a grip inserted in said casing, means connecting said casing and grip so as to be freely movable with respect to one another, grooves in the periphery of the grip for the reception of the finger-tips, and a polishing member mounted in 50 said casing around said grip.

2. Apparatus for polishing finger-nails comprising in combination a casing with an opening 55 at one side, a grip inserted in said casing, means connecting said casing and grip so as to be freely

movable with respect to one another, grooves in the periphery of the grip for the reception of the finger-tips, a polishing member mounted in said casing around said grip, and a handle secured to the casing for its rotation around said grip.

3. Apparatus for polishing finger-nails comprising in combination a box-shaped casing with an opening at one side, a post secured to said casing in the interior thereof and projecting towards said opening, a grip inserted in said casing and mounted freely movable on said post, grooves in the periphery of the grip for the reception of the finger-tips, and a polishing ring in the form of an elastic cushion mounted in said casing around said grip.

4. Apparatus for polishing finger-nails comprising in combination a casing with an opening at one side, a grip inserted in the casing, means connecting said casing and grip so as to be freely movable with respect to one another, grooves in the periphery of the grip for the reception of the finger-tips, a polishing member mounted in said casing around said grip, a crank with a handle on its free end hinged to said casing, and a hole in the casing through which passes said handle if the crank is folded back flat against the casing.

5. Apparatus for polishing finger-nails comprising in combination a casing with an opening at one side, a grip inserted in said casing, means connecting the casing and grip so as to be freely movable with respect to one another, grooves in the periphery of the grip for the reception of the finger-tips, and a polishing ring in the form of an elastic cushion and provided with a wavy polishing face mounted in the casing around the grip.

6. Apparatus for polishing finger-nails comprising in combination a box-shaped casing with

an opening at one side, a grip inserted in the casing, means connecting the casing and grip so as to be freely movable with respect to one another, grooves in the periphery of the grip for the reception of the finger-tips, a polishing ring in the form of an elastic cushion mounted in said casing around said grip, and a tensioning spring attached to said polishing ring for removably securing said ring in the casing.

7. Apparatus for polishing finger-nails comprising in combination two polishing devices; each device consisting of a casing with an opening at one side, a grip inserted in the casing, means connecting said casing and grip so as to be freely movable with respect to one another, grooves in the periphery of the grip for the reception of the finger-tips, and a polishing member mounted in said casing around the grip; and means on each casing for detachably connecting both devices behind each other in a plane and whereby the openings in the casing are disposed at opposite sides with respect to one another.

8. Apparatus for polishing finger-nails comprising in combination two polishing devices; each device consisting of a box-shaped casing with an opening at one side, a grip inserted in the casing, means connecting said casing and grip so as to be freely movable with respect to one another, grooves in the periphery of the grip for the reception of the finger-tips, and a polishing member mounted in said casing around the grip; and means on each casing for detachably connecting both devices behind each other in a plane and whereby the openings in the casing are disposed at opposite sides with respect to one another.

ALFREDO WALDEMAR DOUX.
